Patented Jan. 21, 1919.

UNITED STATES PATENT OFFICE.

RAYMOND T. HILL, OF DETROIT, MICHIGAN.

SCREEN-DOOR CATCH.

1,291,886.

Specification of Letters Patent. Patented Jan. 21, 1919.

Application filed May 25, 1918. Serial No. 236,566.

To all whom it may concern:

Be it known that I, RAYMOND T. HILL, citizen of the United States, residing at Detroit, in the county of Wayne and State of Michigan, have invented certain new and useful Improvements in Screen-Door Catches, of which the following is a specification, reference being had therein to the accompanying drawings.

10 This invention relates to a screen door catch, and has for its object the construction of a simple and efficient catch for holding a screen door temporarily locked or permanently locked at the control of the operator.

15 With this and other objects in view, my invention consists of certain combinations and modifications and advantages, as will be hereinafter more fully described and pointed out, and set forth in the appended claims.

20 Figure 1 is a perspective view of my improved catch showing the same as it appears attached to a door frame and door screen, while

25 Fig. 2 is a similar view, except that the screen is in an open position.

Fig. 3 is a rear view in elevation of the casing and the fastening means carried thereby.

30 Fig. 4 is a sectional view taken on line 4-4 Fig. 3, and looking in the direction of the arrows.

Referring to the drawings by numerals, 1 designates a door frame and 2 the screen door frame.

35 A casing 3 is provided, which casing is open on its under side (Fig. 3), and the casing is provided with apertures 4 in its outer portion for receiving the retaining screws 5 that are provided for attaching the casing 3 and its contained parts to the door frame, as shown.

40 The casing is open also at its front end 6 (Fig. 3), and is provided with a rear closed end 7.

45 Primary spring jaws 8 are positioned in the casing 3 and these jaws 8 are provided at their base with right-angled extensions 8^a, which extensions 8^a lie flat against the end 7 (Fig. 3), and through these extensions or

50 base portions 8^a of the primary jaws 8 extend rivets 9, each rivet being provided with heads upon its ends, the rivets not only perform the function of securely fastening the jaws 8 in the casing, but their inner heads being flat, as shown in Fig. 3, provide a substantial bearing for the curved springs

10. The inner heads of rivets 9 constitute a saving in the construction of the device, for by placing the springs 10 upon these heads a shorter length spring may be used; each 60 spring exerts its greater amount of pressure at its outer ends, 10^a, upon the sides of the casing 3 and the sides of the primary jaws 8.

It is to be noted that the primary jaws 8 are outwardly-bulged at their center to constitute a receiving pocket 8^b, and each jaw 8 is outwardly-flared at its outer end for permitting the ready entrance of the bulged tongue 11 carried by the screen door frame 2.

The tongue 11 is provided with right angularly positioned bases 11^a that engage the screen frame 2, and through these bases 11^a extend screws 12 securely fastening the tongue 11 to the screen frame 2.

When the screen door is closed the tongue 75 11 moves in between the jaws 8, as shown by dotted lines in Fig. 3, and then, by providing aligned elongated apertures 13 in the outer portion of the casing 3, a substantial U-shaped member 14 can be quickly inserted 80 in these elongated apertures 13, straddling the jaws 8 as shown in Fig. 3, and thereby securely fastening the tongue 11 in the casing 3 so that the screen door cannot be opened until the operator removes the locking device 14. The locking device 14 is preferably attached by chain 15 to one of the securing screws 5 (Figs. 1 and 2).

The jaws 8 will ordinarily retain the screen door in the closed position, against 90 accidental opening thereof, such as the door blowing open by the wind, but if it is desired to securely fasten the screen door closed, then all that is necessary is to insert the U-shaped locking device 14 in the apertures 13, after the tongue 11 has entered between the jaws 8.

What I claim is:

1. In a device of the class described, the combination, of a casing provided with a 100 pair of spring jaws, said casing provided with a pair of aligned elongated apertures contiguous to said jaws, a tongue adapted to enter between said jaws, and a locking device inserted in said elongated apertures and 105 straddling said jaws and tongue for fastening said tongue within the casing against accidental displacement.

2. In a device of the class described, the combination with a casing, of spring jaws 110 provided with outwardly-bulged portions and with outwardly-extending outer ends,

said casing provided with elongated, alined apertures at the point of the jaws between their outwardly-bulged portions and their outwardly-extending ends, a tongue provided 5 with a bulged portion adapted to enter between the jaws and be seated between the bulged portions thereof, and a U-shaped fastening member inserted in said elongated apertures and straddling the jaws between 10 their outer ends and their bulged portions, and also straddling the tongue for securely fastening the tongue within the casing.

3. In a device of the class described, the combination with a casing provided with a 15 closed end, of spring jaws provided with right-angularly-positioned base-portions

resting against the closed end of said casing, said jaws provided with outwardly-bulged portions, rivets provided with heads upon their ends, extending through the closed end 20 of said casing and through the base portions of said jaws, curved springs bearing only at their center upon the inner heads of said rivets and pressing at their ends upon the sides of the casing and the outer sides of the 25 bulged portions of the jaws, and a securing tongue normally positioned between said jaws.

In testimony whereof I hereunto affix my signature.

RAYMOND T. HILL.
